UNITED STATES PATENT OFFICE.

HENDERSON WILLARD, OF GRAND RAPIDS, MICHIGAN.

BARREL.

SPECIFICATION forming part of Letters Patent No. 237,943, dated February 15, 1881.
Application filed January 20, 1881. (No model.)

To all whom it may concern:

Be it known that I, HENDERSON WILLARD, of Grand Rapids, Michigan, have invented a new Improvement in Barrels, of which the following is a specification.

5 My invention relates to an improvement in "bent barrels;" and it consists in a bilged vessel constructed of sheets of alternately-gored material, applied together, with the gores of one sheet covered by the material of another sheet, as hereinafter more fully shown and described, my object being to economize material and labor, and to add tightness, strength, and symmetry to the package.

15 In the drawings, Figure 1 is a perspective view of my invention; and Fig. 2 is a plan view, showing the alternate arrangement of gores *c c* and *c' c'*, and an edge view of two gored sheets, *A* and *B*, before the barrel is bent.

20 The longer sheet, *A*, is for the outer, and the shorter sheet, *B*, is for the inner, shell of the barrel, as shown at *A B*, Fig. 1. The gores *c c* in one side of each sheet alternate with the gores *c' c'* in the other side of the sheet—that is to say, they do not exactly oppose each other, so that they would meet and divide the sheet in two if extended to or past the middle of the sheet. By this arrangement of the gores it results that there is less liability of splitting or tearing the sheet apart in handling it,

25 and the sheets more truly fit each other and

readily assume the transverse curves necessary to produce a shapely barrel at all points from chine to chine. In this instance the inner sheet is crozed for the reception of the 35 head-pieces; but I do not limit myself to any mode of securing the heads to the body of the barrel. These sheets are about one-half the usual thickness of common cooperage stock, and the weight of my package is but a trifle 40 more than that of the common package.

It is desirable that each ply be made of only one sheet; but to save material narrow sheets or staves may be inserted in either ply.

The sheets are both of wood or both of paper-board, or are one of wood and the other of paper-board, either being outside. For some purposes the plies should be glued, pasted, or cemented together.

Having thus described my invention, what I claim to have invented, and wish to secure by Letters Patent, is—

A bilged vessel having a body constructed of sheets of alternately-gored material, applied together, with the gores of one sheet covered by the material of another sheet, as and for the purposes set forth.

HENDERSON WILLARD.
